ATTORNEY

UNITED STATES PATENT OFFICE.

BRYANT L. AKINS, OF BROOKLYN, NEW YORK.

DIRECTORY BOARD.

Application filed April 11, 1925. Serial No. 22,255.

To all whom it may concern:

Be it known that I, BRYANT L. AKINS, a citizen of the United States of America, residing at Brooklyn, Kings County, and 5 State of New York, have invented certain new and useful Improvements in Directory Boards, of which the following is a specification.

This invention relates to directory boards 10 and in particular to the construction of the same whereby they may be put up and the names thereon changed from time to time as desired with a minimum of effort and time.

15 A particular object of the invention is to provide a door for directory boards which can be entirely removed prior to changing the names on the board and which will be held in position after being unlocked so that it will not accidentally fall on the ground and be broken.

20 A further object of the invention is to provide a name strip holding member which will retain the strips in proper position and when rearrangement of some of the strips is desired the same can be accomplished without interfering with the other strips.

25 Referring to the drawing wherein I have shown a preferred embodiment of my invention,

30 Figure 1 is a front view of a directory board constructed in accordance with my invention, parts thereof being broken away to disclose the interior,

35 Figure 2 is a section taken on the line 2-2 of Figure 1,

Figure 3 is a section taken on the line 3-3 of Figure 1,

40 Figure 4 is a front view in elevation of the strip retaining plate, several strips being shown in position, and

Figure 5 is an enlarged section on line 5-5 of Figure 1.

45 Figure 6 is a top edge view showing the construction of the strip retaining plate or backboard.

50 Referring to the drawing in detail 5 indicates the border or frame of a directory board constructed in accordance with my invention, the frame being cast to provide ornamental side grooves, and a plurality of openings, 6 of which are for the directory names and 7 of which is for an ornamental plate 8 preferably bearing the name of the 55 building in which the directory is hung or,

as shown in the drawing, the word "Directory" may be cast integral with the plate 8, the plate being held in position in the opening 7 by soldering, welding or bolting to the flange pieces 9 which border the opening 7 and are held in position against the frame 5, in any suitable manner.

Extending around the interior of the frame 8 and suitably attached thereto is the border 10 which is composed of pieces of 65 angle iron which fit into the corners of the frame 5 and are held in their rectangular form by suitable corner braces 11 which are riveted thereto. Upon this interior border 10 I provide a connecting channel iron 12 70 which connects the top and bottom pieces of the frame and which passes over a plurality of connecting strips 13 which join the sides of the border 10 the strips 13 and channel iron 12 constituting a base to which the 75 frame 5 is bolted or otherwise suitably secured. In smaller directory boards the vertical channel iron 12 may be dispensed with.

The frame 5 is substantially channelled shape in cross section and in the directory 80 board openings 6 there fits doors 14. A description of one door, it is thought, will suffice. The door frame 15 is made of angle iron and has in its lower portion an elongated opening 16 and in its front lower portion a round opening 17 which is adjacent the opening 16 and in which is adapted to be held by soldering, force fit, or otherwise a ferrule 18 in which is disposed the outer end of a bolt carrier 19, the inner end of 85 which is journaled in an opening 20 in the upstanding portion 21 of a standard 22 which is welded to the bottom of the door frame. The bolt carrier 19 at its outer end is slotted as at 23 and at its midportion 90 carries the bolt or latch 24 pinned thereto which is adapted to be swung into and out of engagement with the inside edge of the frame 5. The bolt is operated by placing the end of a screw driver or like tool in the 95 slot 23 and revolving the bolt carrier.

The door is not connected in any way with the frame 5, but the door frame 15 has at its center top portion an upwardly projecting lip 25 which engages the inside of 105 the frame 5 after the manner of the bolt when the same is turned down to locking position.

In most doors of this character difficulty 110 has been experienced in getting the door

out when the names on the directory are to be changed, and in order to not only overcome this objection but to also provide an improved name strip holder I provide a special strip holder 26 made of resilient spring metal, consisting of a plate piece 27 the sides of which are bent as at 28 to form receptacles for the ends of the name slips 29, the center of the plate 27 being offset at 30 and curved outwardly. Openings 31 are provided in the plate 27 to match screw holes 32 provided directly thereunder in the extended free edges 33 of elongated strips 34 welded or otherwise secured to the plate 27 and extending the length thereof. These strips 34 are attached through the medium of screws 34^A to the cross pieces or strips 13 and provide a yieldable bearing for the plate or backboard 27, the center of which is bulged outwardly so that it will hold the name strips 29 which are made of heavy composition board in place. When the door is placed in position the glass thereof which is held in position in any suitable manner such as by wedge blocks 35 shown in Fig. 2, presses against the name strips and causes depression of the bulging portion 30, and therefore holds the name strips from slipping. In placing the door in position, the same is manipulated until the tip 25 passes up behind the edge of the frame 5, and then the lower edge of the door is moved into position until the bolt can be revolved to lock the same in position. When the door is in closed position the name strip backboard is tending to push it out, and when the lock is operated to release the bottom of the door the lower end of the same is swung out by the spring tendency of the backboard. When the door is moved out by the backboard its upper end is resting between the upper edge of the backboard 27 and the inner edge of frame 5, so that by its own weight it presses the lip hard enough against the edge of the frame to prevent the door sliding out, until it is raised to an oblique position relatively to the directory board where it can be readily drawn out. Thus the removal of the door is made very easy and when it has been entirely removed, the bulge 30 in the backboard 27 prevents any sliding movement of the name strips as it bends them out and their ends are held in the turned over side edges 28. Thus, as shown the name strips 29 can be snapped into the backboard in contact with each other or in spaced relation and will remain where placed.

The backboard openings 31 and screw holes 32 are elongated so that adjustment can be made by loosening the screws 34^A which hold the plate or backboard 27 and the backboard shifted up or down as desired.

It is evident that I have provided an im-

proved directory board and one in which the name strips can be readily changed without complete rearrangement. Also the door can be removed without danger of its falling to the ground and becoming damaged. 70

Having described my invention what I claim is:

1. A directory board comprising a frame, bracing members connecting the parts of said frame a depressible curved backboard attached to said bracing members, strips held in said backboard, and means associated with said backboard for frictionally retaining the strips in position. 75

2. A directory board comprising a door a yieldable outwardly curved backboard behind said door and normally pressing against the same, name strips adapted to be placed in the backboard and means formed in said backboard for maintaining the strips therein in any position relatively to each other. 80

3. A directory board comprising an ornamental frame, a name strip holding element therein, a removable door for covering and flattening out said element, and said element being curved for resiliently maintaining said name strips against the door when the latter is in closed position in the frame. 90

4. A directory board comprising a frame, an arcuate shaped name strip holding element therein, a door removably associated with said frame and normally urged outward by said element, a lip on the top of said door adapted to engage the frame, and a locking member in the bottom of said door adapted to cooperate with the lip for preventing premature removal of the door from said frame. 95

5. A directory board name strip holding member comprising a resilient plate having its longitudinal edges turned to provide grooves, and having an offset central bulging portion for retaining the name strips in the position in which they are placed in said holding member, and said holding member being normally curved outwardly. 105

6. A directory board comprising a frame having a plurality of openings therein, a name plate in one of said openings, name slip holding members in the other openings, removable doors in said last mentioned openings, locking means for normally retaining said doors in closed position, and means associated with said slip holding members for causing an outward swinging of the doors when the latter are unlocked. 115

7. A directory board comprising a frame, a cast name plate therein, a name slip backboard in said frame having a normally bulging resilient portion, means for holding name strips in said backboard, a transparent door separably associated with the frame and adapted to cover said name strip holding backboard, means for locking said door 125

in position in the frame, the door when in position causing depression of the back-board, reinforcing strips on said frame, and means in said backboard for adjusting the 5 same relatively to said reinforcing strips.

8. A name strip holder for directory boards comprising a resilient plate having a

central bulged portion, and turned edges into which fit the ends of name strips, reinforcing strips on the back of said plate having portions spaced from said plate, and said plate and said strips being provided with matching openings therein.

BRYANT L. AKINS.
